UNITED STATES PATENT OFFICE.

HARRY J. HICK, OF ALLIANCE, OHIO, ASSIGNOR, BY MESNE ASSIGNMENTS, TO THE
McCASKEY REGISTER COMPANY, (INCORPORATED IN 1914,) OF ALLIANCE, OHIO,
A CORPORATION OF OHIO.

FILING APPLIANCE.

1,276,356.

Specification of Letters Patent. Patented Aug. 20, 1918.

Application filed June, 26, 1911. Serial No. 635,354.

To all whom it may concern:

Be it known that I, HARRY J. HICK, a citizen of the United States, residing at Alliance, in the county of Stark and State of Ohio, have invented certain new and useful Improvements in and Relating to Filing Appliances, of which the following is a specification.

This invention relates to filing appliances 10 adapted for filing, holding and keeping papers or documents, enabling them to be removably held in classified arrangement, and also permitting their ready inspection, and the making entries on them.

15 For the purpose of illustration, I have, in the accompanying drawings, shown and herein described one form of filing appliance embodying my invention.

Figure 1 is a side elevation of a filing appliance embodying my invention, the casing being shown in section.

Fig. 2 is a side elevation of the appliance, similar to Fig. 1, with some of the holders of one set in operated position.

25 Fig. 3 is a front elevation, a portion of one set of holders being broken away.

Fig. 4 is a fragmentary perspective view of one of the swingable supporting members.

30 Figs. 5 and 6 are fragmentary sectional views illustrating details of construction.

In the drawings:

1 indicates a casing. It may be of any suitable or preferred construction. In the form of construction illustrated in the drawings, it comprises a bottom 1^a, a back or rear wall 1^b, and sides 1^c, which may rise vertically at their rear portions to a height coincident with the top of the back 1^b. A bar or plate 1^d may connect the upper ends of the

40 sides 1^c together. Being secured thereto and also secured along its rear edge to the top edge of the back 1^b, the said plate serves to strengthen the casing.

2, 3, indicate two sets or series of holders, 45 the holders of each set being arranged face to face, and arranged to support or carry papers or documents. As will be later described, the supports for the holders of each set 2, 3, permit them to swing singly or in 50 groups from one position to another, whereby either face of each and every holder may be exposed. The holders 2 are arranged normally in upright position and swing to a horizontal position, while the holders 3

normally occupy a horizontal position and 55 swing to a vertical position.

Each holder 2 preferably comprises a back 2^a, formed from sheet metal, a series of paper engaging and holding devices 2^b, and strips 2^c, which space the backs from each other, form pockets or side walls for the papers, and may also strengthen the backs from end to end. The holding devices 2^b and the strips 2^c may be arranged upon either or both faces of each holder.

2^d indicates suitable connections between the holders 2 and permitting them to swing relative to each other from the normal position to the reclined position, and vice versa. The series of holders 2 is preferably pivotally supported at its front end, a pair of pivot blocks 4, mounted on a support 4^a, being provided therefor and arranged in a plane above the set of holders 3, with the rear holder of the series resting against the back 1^b. The supports 4 serve as the pivot for the front holder 2 and are preferably arranged to permit the ready removal of the entire set of holders 2, bodily, from the casing 1 for storage in a safe or vault.

As will be understood, when the set of holders 2 is supported at its front, and the front holder thereof or any succeeding holder is reclined, the connections 2^d cause the lower edges of the remaining upright 85 holders to move forwardly and may at the same time effect a bodily upward movement of said remaining upright holders.

5 indicates suitable means for guiding the rearmost holder 2 during the operation of 90 any of the holders in that set, the dotted lines in Fig. 1 illustrating the guiding means in operative position.

Each holder of the set of holders 3 is 95 preferably constructed similarly to the holders 2. The holders 3 are connected together at their inner ends by devices 3^a, which permit them to swing relative to each other from one position to another.

6 indicates a vertical wall, guide or abutment arranged approximately in the vertical plane with or slightly forward of the supports 4. This wall serves as a back or abutment for the holders 3 and also as a guide way to permit up and down movements of 100 the upper end holder 3 during the operation of any of the holders from one position to another, as will be later described.

7 indicates as an entirety mechanism which movably supports the set of holders 3. This mechanism may comprise one or more pairs of links 7^a, each link being pivotally connected to one end, for instance at their upper ends, at 7^{a'}, to the adjacent side 1^c of the casing and at its opposite end to the lowermost holder 3 of the set of holders.

As shown in the drawings, the links 7^a 10 depend downwardly from their pivots 7^{a'} the weight of the holders 3 causing them to hang vertically when all the holders are in normal position. When endwise movement of the holders 3 away from the abutment 6 15 takes place, the links will swing outwardly and upwardly and thus elevate the holders and when the holders 3 move endwise in the opposite direction the links swing downwardly and inwardly. As all the links move 20 together about their respective pivots, those holders 3, not operated will remain in a horizontal position during their swinging movements in endwise directions. The links are preferably of equal length and arranged 25 on opposite sides of the holders, one pair of links being arranged near or adjacent the inner or pivoted ends of the holders 3, and the other pair being arranged near or adjacent the outer or free ends thereof.

30 7^b indicates a bar connecting each set of links together whereby they are made to swing together and thus obviate binding in their bearings. The links 7^a and bars 7^b may be formed integrally from a strip of 35 metal which is bent into substantially U-shape, as shown in Fig. 4, thus forming a rocking or swing frame on which the holders rest.

8 indicates a horizontal table for the holders 3 interposed between the lowermost holder of the set and the bars 7^b. The table 40 8 serves as a rest for the holders 3 and permits them to be removably mounted on or connected to the swinging mechanism 7. 45 The detachable connections between the table and lowermost holder 3 may comprise a flange 8^a along the rear edge of the table and a turned over edge 8^b extending along its front edge. When the holders are 50 mounted on the table 8, the free edge of the lowermost holder is first inserted within or below the turned-over edge 8^b and then its inner end is dropped down within the flange 8^a. This latter flange thus serves to 55 hold the front or free edge of the holder under the flange or edge 8^b, which in turn prevents the removal of the holders, without first elevating the inner ends thereof to bring the lowermost holder above the 60 flange 8^a.

8^c indicates a flange extending along either side of the table. These flanges may be provided in order to prevent the holders from moving laterally on said table.

65 8^d indicates a plurality of hinge devices,

such as metal straps 8^e fixed to the under side of the table and each passing through a slot or opening 7^c formed in the connecting cross bars 7^b. These hinge devices serve to form, through the bars 7^b, pivotal connections between the table 8 and links 7^a.

As shown in Fig. 1, the holders 3, when in normal position, are superposed relative to each with their inner or hinged ends against or parallel to the wall 6. A slide member, 75 such as an anti-friction roller or wheel 3^b, is preferably interposed between the upper end holder and wall 6, which holds the inner ends of the holders slightly separated from the wall.

9 indicates a frame which is pivotally connected along its inner or rear edge to some stationary part of the casing 1, whereby it can be arranged in a horizontal position, as shown in Fig. 1, or moved to a vertical position as shown in Fig. 2. The frame preferably lies in the plane of and is hinged to the forward edge of the support 4^a. The latter may be cut away to form a ledge 4^b and the opposite inner faces of the sides 1^c 90 may be formed with shoulders 1^{c'} to support the opposite and side and rear edges of the frame 9 when it is in horizontal position.

The frame 9 is common to both sets of 95 holders 2, 3, and operates as a rest or support for the free ends of the holders of either set which may have been operated at any time. When the holders of both sets are in normal position, the frame 9 may serve as a desk or writing board. It may also carry on 100 its upper face an index or list of the headings, titles or signaling means for the paper holding devices 2^b carried by the set of holders 2 and also a separate index or list on its under face for the paper engaging devices 2^b 105 carried by the set of holders 3.

Prior to the operation of the holders 3, the frame 9 is swung to the position shown in Fig. 2 with its upper edge resting against the set of holders 2. As the frame 9 is preferably pivoted slightly forward of the blocks 4, it will remain in upright position, although other means may be provided for holding it in that position.

By the operation of one or more holders 3 115 from the horizontal to the vertical position, the connections 3^a between the holders effect an outward or endwise movement of those holders 3 remaining in horizontal position and the table 8, and at the same time those 120 holders which have been operated to the vertical position will move downwardly. This outward movement away from the wall 6 and the downward movement of the operated holders will be in proportion to the 125 number of holders operated at any one time.

The table 8 being connected to and supported on the swinging mechanism 7, the latter will permit the table and holders to move outwardly during the operation there- 130

of and at the same time it will elevate them; that is, each time a holder or group of holders 3 is operated to the vertical position the swinging and elevating mechanism 7, while 5 permitting those holders which remain in the horizontal position to move outwardly or away from the wall 6, will elevate them more and more until all the holders 3, except the lower end holder 3 (which is connected to the table 8) have been operated. Operation of the holders 3, singly or in groups back to the horizontal position will effect a downward and rearward movement of the swingable supporting mechanism 7 to 10 its lowermost or normal position.

3^b indicates an anti-friction device carried by the upper end holder 3 and serving to avoid friction between the frame 9 and the said holder (see Fig. 2) in its up and 20 down movements during the operation of the remaining holders.

The frame 9 and wall 6 are preferably arranged approximately in line with each other so that the operated holders 3 will be 25 supported in a substantially vertical position.

In the operation of the holders 3, the opposite end holders of the set always remain at substantially right angles to each other as any of the holders between them are operated 30 about their respective pivots, the holders not operated being supported in horizontal position during their outward and upward movement. It will thus be seen that as the holders 3 are operated, the opposite 35 end holders have a simultaneous movement, one moving downwardly and the other upwardly.

The movable supporting mechanism for the holders 3 not only permits the outward 40 movement of the unoperated holders in a direction substantially at right angles to the direction of movement of those^b holders which have already been operated, but operates to elevate the unoperated holders and 45 move them toward the operator, this latter operation continuing until all the holders (except the lower end one) are operated.

To those skilled in the art of making filing appliances of the class described, many alterations in construction and widely differing embodiments and applications of my invention 50 will suggest themselves, without departing from the spirit and scope thereof. My disclosures and the description herein are 55 purely illustrative, and are not intended to be in any sense limiting.

What I claim is:—

1. In a filing appliance, the combination 60 of a casing having an upright abutment therein, a series of holders normally arranged in reclined position and having connections between them whereby they may be rotated to and from an upright position, pairs of parallel links having their upper 65 ends pivoted to the case, and a table piv-

oted to the lower ends of the links bodily supporting the holders, the upper holder being adapted for sliding contact with the abutment and the lower holder being removably mounted on the table for swinging the 70 same forward when one or more holders are rotated from reclined to upright position.

2. In a filing appliance, the combination 75 of a casing, a series of holders normally arranged in horizontal position and having connections between them whereby they may swing relative to each other to a vertical position, the upper end holder of the set being adapted for sliding engagement with the casing when in operative position and link 80 mechanism for swingably supporting the said holders, the said mechanism including a horizontal table carried by a pair of U-shape members pivoted at their upper ends to the casing and operating, when any of 85 the holders are operated about their respective pivots, to swing the remaining horizontal holders outwardly and upwardly.

3. In a filing appliance, a casing having 90 a guide wall, sets of links pivotally connected at their upper ends to said casing, a series of holders normally supported by said links in horizontal position and having pivotal or rocking connection therewith, and connections between the holders permitting 95 them to swing relative to each other from the horizontal to a vertical position, the upper end holder of the series of holders being adapted for sliding engagement with said guide wall when in operative position and 100 the sets of links operating to maintain the unoperated holders in horizontal position as said links swing about their pivots.

4. In a filing appliance, the combination 105 of a casing, a series of holders normally arranged in horizontal position in said casing and having connections between them permitting the said holders to swing relative to each other, a pair of U-shaped members arranged transversely of the holders at or 110 near their outer and inner ends, respectively, means for swingably supporting said U-shaped members in the casing at their opposite ends, and an abutting wall arranged to be slidably engaged by the upper end 115 holder of the series, a horizontal table carried by the pendent ends of said links forming a support for said holders, whereby when any of the holders are operated about their respective pivots the U-shaped members 120 swing outwardly and upwardly.

5. In a filing appliance, the combination 125 of a casing, a series of holders normally arranged in horizontal position in said casing and having connections between them permitting the said holders to swing relative to each other, a pair of U-shaped members arranged transversely of the holders at or near their outer and inner ends, respectively, means for swingably supporting said U- 130

shaped members in the casing at their opposite ends, an abutting wall arranged to be slidably engaged by the upper end holder of the series, a horizontal table carried by the pendent ends of said links forming a support for said holders, and pivotal connections between the lower end holder and the U-shaped members operating to move the said members simultaneously whereby the operation of the holders about their respective leaves will swing the U-shaped members outwardly and upwardly and maintain the holders remaining in normal position horizontal during such movement.

6. In a filing appliance, the combination of a casing having an upright abutment therein, a series of holders normally arranged in reclined position and having connections between them whereby they may be

rotated to and from an upright position, 20 pairs of normally pendent links pivoted for swinging in the case, and a table carried by the links bodily supporting the holders, the upper holder being adapted for sliding contact with the abutment and the lower holder being removably mounted on the table for swinging the same forward and upward when one or more holders are rotated from reclined to upright position, whereby the weight of the holders tends to 25 swing the table rearward to normal position.

In testimony whereof I affix my signature in the presence of two witnesses.

HARRY J. HICK.
